CLAIM

The ornamental design for a display screen or portion thereof with graphical user interface, as shown and described.

DESCRIPTION

FIG. 1 is a front view of a display screen or portion thereof with graphical user interface, showing my new design; and, FIG. 2 is a front view thereof, in which a mobile terminal in broken lines is provided to illustrate an example environment. The broken line showing of a display screen and elements of a user interface are included for the purpose of illustrating portions of the article and form no part of the claimed design. The broken line showing of a mobile terminal is included for the purpose of illustrating environmental structure and forms no part of the claimed design.
